UNITED STATES PATENT OFFICE.

LAWRENCE X. CHAMPEAU, OF NEW YORK, N. Y., ASSIGNOR, BY MESNE ASSIGNMENTS,
TO KIRBY INCORPORATED, A CORPORATION OF NEW YORK.

LIGHTING APPARATUS.

Application filed June 17, 1924. Serial No. 720,493.

This invention relates to lighting apparatus for galleries, school rooms, exhibition halls, museums, and certain types of factories, shops, and work or other rooms in which it may be desirable to distribute the light according to a predetermined plan.

The principal object of my invention is to direct daylight into interiors to produce a maximum illumination and even distribution of the light admitted over the desired portions of the interior, while maintaining a relative darkness in other portions where this condition may be advantageous.

One embodiment of the invention has been illustrated in the accompanying drawings, in which

Fig. 1 is a vertical sectional view through a room, showing the device in use;

Fig. 2 is a plan view of one of the refracting units making up the ceiling;

Fig. 3 is a transverse section at right angles to the axes of the prismatic portions of such a refracting unit on a greatly enlarged scale;

Fig. 4 is an elevation of such a unit as seen from the right of Fig. 3;

Fig. 5 is a perspective view taken diagonally of the room, as viewed from a point between the ceiling and one form of light deflecting structure;

Fig. 6 is a cross section on an enlarged scale through a combined light intercepting and refracting unit, taken on line 6-6 of Fig. 8;

Fig. 7 is a transverse view through the upper part of a room employing the light controlling apparatus shown in Fig. 6; and

Fig. 8 is a plan view of part of a ceiling of the type shown in Fig. 7.

In art galleries the paintings to be viewed are hung along the walls at some distance above the floor, and should be more or less evenly illuminated over their entire surfaces.

For efficient use of the available space, the portions of the walls near the corners of the gallery should be as brightly lighted as the central portions in order that pictures hung at any point may be viewed to equal

advantage. Again it is desirable that paintings should be hung behind protecting glass, but prior to this invention it has not been customary so to protect pictures on exhibition, because the view of observers has been so marred by reflections seen in the cover glass as to prevent proper appreciation of the paintings themselves.

This invention solves these problems of art gallery lighting, first, by admitting light through a skylight past a suitable interceptor to a refracting ceiling which directs the incident light rays toward the walls, leaving the central space directly beneath the ceiling relatively dark. Thus an observer standing at the usual distance from a painting hung on the wall, always has his back toward the source of light and the whole front of his body is in the shadow, so that he can see his reflection in the cover glass on the pictures but dimly, if at all. The refracting ceiling also directs sufficient light into the corners of the room, that pictures hung on any part of the wall appear to equal advantage.

In school rooms, library reading rooms, work shops for the needle trades, and various machine shops in which the operatives face constantly in the same direction, it is desirable that light should all come from above and to the rear of the persons in the room, so as to pass diagonally over their left shoulders upon their work. This desirable result may be easily attained by one form of the present invention, in which the refracting ceiling is made up of transparent material, such as glass having a multiplicity of parallel prisms extending diagonally across the room.

In the northern hemisphere the sun, at places in latitudes greater than $23\frac{1}{2}^{\circ}$, always crosses the meridian south of the zenith, so that if its rays were directly admitted to the room to be illuminated, the north wall would receive more light than the south wall. In order to obtain uniform distribution of the light which strikes the refracting ceiling of this invention, any usual light in-

intercepting structure may be interposed between the transparent roof and the ceiling of the room to be illuminated. Where the very best results are desired and the expense of installation is a secondary consideration, the light deflecting structure is preferably of the type shown in applicant's Patent, No. 1,419,918, and which has been illustrated in Figs. 1 and 5 of the present application. In these figures, 9-9 designates the easterly and westerly walls of the room to be illuminated, while the north or south wall is indicated at 10. All the light is admitted through a transparent roof 11, which, in the case of art galleries, may be of considerably smaller area than that of the floor 12. Between the ceiling 13, which is formed of transparent refracting material to be described, and the roof is an interceptor which consists of a series of suitably spaced deflecting members 14 which extend in a general east and west direction, and are mounted for rotation on horizontal axes. Between adjacent members 14 and supported for movement on vertical axes, as described in applicant's patent above referred to, are additional reflecting members 15, the position of which may be varied in accordance with the position of the sun to prevent direct rays of the sun from striking the ceiling 13. By properly operating the deflectors described, the course of rays of light passing through the roof 11 may be altered so that by far the greater portion of the light will pass more or less vertically downwards from the deflectors to the upper surface of the ceiling.

The arrangement of the prisms in the ceiling differs according to the particular lighting requirements of the room to be lighted. In the case of an art gallery where pictures are hung on the four walls, the ceiling is divided up into four sections of approximately equal area, designated in Fig. 5 as N. E., N. W., etc. according to the points of the compass. Each section of the ceiling consists of one or more refracting plates 16 arranged to bend the nearly vertical rays incident on its upper surface away from the center of the room. For convenience in installation and economy of manufacture, each section of the ceiling is made up of a sufficient number of rectangular plates supported on mullions 17 running in one direction intersected by transverse mullions 18. Each plate preferably has a plane lower surface, while its upper surface is sub-divided into a plurality of prisms 19 having parallel axes. The particular angle of the prisms is governed by the optical qualities of the glass, or other transparent material of which they are composed, and by the dimensions of the room to be lighted. Thus in the gallery shown in Fig. 1, the prism plates are designed to refract a vertical ray of light to

an angle of approximately 45° with the vertical. By arranging the axes of the prisms in each section of the ceiling parallel to each other and at such an angle to the side walls that a line at right angles to the axes of the prisms is parallel to a diagonal of the room, namely, the line passing from the center to the corner, the light below the ceiling is refracted in the general direction of the corners of the room. That light which passes through the interceptor and strikes the prismatic ceiling at other angles than 90° is, of course, refracted somewhat differently so that not all the light goes into the corners, but by a little experimentation in positioning the deflectors, it will be found that the central parts of the walls being nearer the center of the ceiling than the corners receive more of these nonvertical rays of light and may be illuminated to very approximately the same degree as the corners.

By a consideration of the foregoing in connection with the illustration in Fig. 1, it will be seen that a great deal more light is directed toward the walls than leaks straight down through the ceiling, so that the floor of the gallery is relatively dark and observers standing a little removed from the walls, as they must be to see the subjects hung for exhibition, are so dimly lighted as to cause little or no reflection in the cover glasses of the exhibits.

To produce still more even distribution of the light than can be obtained by the use of prisms having plane faces, it is desirable that the more nearly horizontal surfaces of the prisms should be irregularly curved, as illustrated in Figs. 3 and 4. Thus the rays incident on the one surface of the prism in a vertical plane, as shown at 20, are not refracted into a plane but into a wavy surface in which the most deflected rays follow the path 21 shown in full lines, while the least deflected follow the dotted path 22, and the other rays are deflected between these limits. The use of such irregular prismatic glass in the ceiling entirely does away with any shadow which the light deflecting structure might otherwise appear to cast, and so breaks up light passing through the ceiling that an observer standing on the floor cannot see distinctly any object above the ceiling. Moreover, the use of such irregular prism plates enables satisfactory results to be obtained in many instances by the aid of much simpler light deflecting structures than that above described.

In Figs. 6, 7 and 8 I have shown such a simplified light deflecting structure in which the deflectors are closely adjacent the upper face of the prism plates. In this construction each prism plate supports a cellular light deflector preferably composed of thin metal sheets 23 in parallel spaced rela-

tion, which are intersected at right angles by similarly arranged sheets 24, each sheet being cut partly through at its intersections with cross sheets, so that the deflector as a whole resembles an egg-crate. The sheets are preferably painted white or otherwise treated to make them good light reflectors. The deflector and prism plate are housed in a dust-proof box having vertical side walls 25, three of which have integral upper flanges 26 and lower flanges 27 adapted to grip the edges of cover plate 28 and prism plate 16, respectively. These plates slide into place in the box and may be removably secured by separate upper and lower flanges 29, 30 fastened on the fourth side of the box as by screws 31. The cover plate 28 is a thin sheet of plane surfaced transparent glass 28, which with its surrounding flanges 20 serves to exclude dust from the light deflector and the upper face of the prism plate, thereby greatly decreasing the difficulty and expense of keeping these surfaces clean.

25 The light deflecting boxes may be made up in standard sized units ready for installation upon supporting mullions, which preferably consist of inverted T rails, as shown at 32. In case of damage to any part of such a box, it may be readily lifted out and replaced so that there need never be serious interruption in the lighting of a room using such combined deflecting and refracting units.

35 The relative depth of the deflecting sheets 23, 24 as compared to their distance apart is a matter controlled by the latitude of the place where the lighting apparatus is installed and the particular requirements of any given installation. For example, in latitude 40° the sun at the summer solstice has a zenith distance of only 16½°, so that if it is required that no direct rays of the sun strike the prism plate, the depth of the deflecting sheets must be nearly 3½ times as great as their horizontal distance apart. As this proportion would in some cases admit too little light during the winter season, it has been found desirable to make the sheets 40 about twice as deep vertically as their horizontal separation, and to provide a series of 50 east to west extending shutters 14 above the deflecting refracting structure, as shown in Fig. 7.

55 However, for many uses such as in work shops, school rooms, and other places where people sit facing more or less continuously in the same direction, a little direct sunlight striking the prism plates for a short time 60 each day during the weeks near the summer solstice, is not seriously harmful, and the shutters may be dispensed with. For installations where it is desired to have all the light rays in the room directed approximately in the same direction, as over the left

shoulders of the people in the room, the ceiling consists of a single section in which the axes of all the prism plates are parallel to each other, and to a line running obliquely from the right-hand rear corner of the room 70 to a point on the left-hand wall nearer the front of the room. The exact location of the axes of the prisms, as well as the shape of each prism, of course varies according to the use of the room and the particular type 75 of light deflecting structure which is placed above the refracting ceiling.

While the irregularly wavy surfaced prisms shown in Figs. 3 and 4 break up the light very satisfactorily so as to give a well-distributed illumination below, good results may in many cases be obtained by the use of plates having plane surfaced prisms. The invention is not limited to any specific deflecting or refracting means, but is believed 80 to include all suitable combinations of deflecting and refracting means to control light admitted through a skylight to a place to be illuminated. While only a few of the many varieties of rooms which can be lighted advantageously by the use of this invention have been enumerated, it is believed that better results can be obtained in lighting the top floor of almost any building with this invention than could be obtained through 85 the use of windows in the vertical walls.

What I claim is:

1. In a lighting apparatus, a room to be lighted, an approximately rectangular prismatic ceiling divided into four sections by intersecting lines from the centers of opposite room walls, the apices of the prisms being up and the axes of the prisms in each section being diagonal, the angles of the prisms being so chosen as to direct light falling 100 substantially vertically thereon into the corners of the room to be lighted, and means for controlling the light falling on the upper surface of the ceiling.

2. In a lighting apparatus in combination, 105 a skylight, cellular light-deflecting members below the skylight and having deflecting sides arranged to deflect light coming from an angle into a substantially vertical downward direction, a prismatic ceiling beneath 110 said deflecting members consisting in prisms with their apices up and having their axes and angles so chosen as to refract the light impinging thereon into definite predetermined directions in the room.

3. An apparatus according to claim 2 in which the deflecting members are adjustable.

4. In a lighting apparatus, a skylight, approximately horizontal mullions below the skylight, cellular light deflectors supported by the mullions, prismatic plates below the light deflectors having prisms with the apices up and prism axes and faces so chosen as to refract the light passing through each plate 125 130

in a definite predetermined direction in the plurality of vertical sides, flanges at the bottom edges of the sides to receive and hold 10

5. An apparatus according to claim 4 in which the top of the ceiling formed by the a refracting plate, and vertical light reflect-

5 prismatic plate and cellular light deflectors Signed at Lakeport, N. H., this 14th day
is covered with a transparent plate to form of June, 1924.

a dust-tight box.

6. In lighting apparatus, a box having a
